UNITED STATES PATENT OFFICE.

ADOLOR HAMEL, OF CHICAGO, ILLINOIS, ASSIGNOR OF ONE-HALF TO WALTER W. FULTON, OF CHICAGO, ILLINOIS.

MOLDING APPARATUS.

1,138,558.

Specification of Letters Patent.

Patented May 4, 1915.

Application filed February 16, 1911. Serial No. 609,034.

To all whom it may concern:

Be it known that I, ADOLOR HAMEL, a citizen of the United States of America, and resident of Chicago, Cook county, Illinois, 5 have invented a certain new and useful Improvement in Molding Apparatus, of which the following is a specification.

My invention relates to apparatus for molding cement or concrete structures or 10 articles.

It relates more particularly to apparatus of this kind for making columns or uprights in a building.

Prior to my invention it was quite common to employ stove bolts or similar fastening devices for securing together the different sections of the sheet iron molds employed, for example, in making the cement or concrete columns of a building. This 15 method, however, has been found to be rather expensive, as it will very often require some time for a workman to adjust all the bolts in place. This is especially true after the bolts have become rusty. Another 20 objection is a tendency of the sheet iron to spread or open up between the bolts, unless the latter are placed very close together, or unless the sheet iron is very thick, neither one of which is liable to be the case in actual 25 practice.

My invention contemplates, therefore, a molding apparatus for this general class of work, in which the sections of the mold have their meeting edges provided externally 30 with grooves or channels extending longitudinally of the mold, and in which the means for holding the said sections together consist of clamps provided with elongated jaws that fit within and extend along the said 35 grooves or channels, whereby the mold can be very readily and very quickly set up or taken apart, and whereby the sheet metal, when the mold is set up and filled, does not tend to spread or open up at the seams 40 formed where the edges of the sections are held tightly together, as will hereinafter more fully appear.

To the foregoing and other useful ends my invention consists in matters hereinafter 45 set forth and claimed.

In the accompanying drawings, Figure 1 is a side elevation of the mold and clamps comprised in a molding apparatus embodying the principles of my invention, the 50 same being shown set up and arranged in

position for forming a column, and it being understood that for convenience of illustration only a few of the requisite number of clamps are shown adjusted in position to hold the sections of the mold together. Fig. 60 2 is an enlarged side elevation of one of the said clamps, showing a fragment of the mold. Fig. 3 is a view looking down upon the devices shown in Fig. 2.

As thus illustrated, the mold A is hexagonal in cross-section, being composed of two vertical sections or complementary halves a and a', each section or half being provided at its vertical edges with flanges a² that have their outer edges formed with bent or outwarded portions a³, as shown more clearly in Fig. 3, whereby the said flanges are in effect provided externally with channels or grooves extending longitudinally thereof. The inner surfaces of said flanges bear flatwise upon each other, when the two sections or halves are in position, whereby the interior of the mold is effectively sealed at the sides thereof. The clamps B, which are applied to said flanges, are all alike and the description 65 of one will be sufficient. Referring to Figs. 2 and 3, therefore, it will be seen that the clamp B comprises a pair of elongated jaws b which are adapted to fit in the channels or 70 grooves of said flanges to clamp the latter 75 tightly together. The two jaws are connected by a bolt b' having a thumb-nut b², said bolt being located close to said jaws. For 80 this purpose the jaws are provided with shanks or arms b³ and b⁴, which extend at 85 right-angles to the jaws and for some distance beyond the said bolts by which the jaws are connected. At its outer end the shank or arm b³ is provided with a cam b⁵ having a handle b⁶, which cam is adapted to 90 operatively engage the shank or arm b⁴, being pivoted by a screw or bolt b⁷ inserted through the outer end of the shank or arm b³, which latter, it will be seen by reference 95 to the drawings, is bifurcated to receive the 100 said cam. By operating this cam the jaws can be made to grip or release the flanges of the mold. Screws b⁸, having threaded engagement with the shanks or arms b³, can be 105 employed to bear against the shanks or arms b⁴ to force the jaws together. These screws can be used in conjunction with the said cams, or either the cams or the screws can be used alone. Any suitable devices can be 110 used for operating the jaws of the clamp.

In practice, as many of the said clamps are employed as are necessary to hold the two sections of the mold together. If the sheet metal is quite thin, the said clamps will necessarily have to be arranged quite closely together to prevent the cement or concrete from forcing the meeting edges apart between the clamps. With a thicker metal the sections of the mold can be effectively held together with a less number of clamps—that is to say, without arranging the latter so close together. With this arrangement the mold for even a very large column can be set up and adjusted in place very quickly, and then as easily taken apart.

The clamps can be made of any suitable material, such as metal or wood, and they can be made of different lengths. For some kinds of work it is possible that a single clamp at each side of the mold will be sufficient. In other cases several clamps will be necessary at each side of the mold. The clamps shown have perfectly straight jaws, but it is obvious that these jaws can be variously shaped to accord with the design of any particular column.

Thus it will be seen that I provide an improved molding apparatus which entirely obviates the necessity of employing the stove bolts or similar fastening devices which, prior to my invention, were inserted through the flanges of the mold, and which were so troublesome and unsatisfactory under the old method of doing this kind of work. My invention tends, therefore, to reduce the cost of building construction.

As shown, each clamp has the jaws thereof connected together at their opposite ends, the construction shown in Fig. 3, for example, being simply duplicated at the opposite end of the jaws. It will be understood, however, that as many of these connections can be employed between the jaws as are necessary for any particular length thereof. The effect of the outwardly bent edge portion a^3 is to prevent the said jaws from slipping off while the mold is in use.

What I claim as my invention is:

1. A molding apparatus of the class set forth, embodying mold sections having out-

wardly extending flexible sheet metal flanges at their meeting edges, the outer face of these flanges being shaped to form channels extending along the flanges, and a series of clamping devices connecting said channel flanges at intervals, each of these devices consisting of a pair of elongated clamping bars slidably engaging the channels, each pair of said bars carrying means for removably clamping them upon said flanges at any desired point. 55

2. A molding apparatus of the class set forth, embodying mold sections having outwardly extending flexible sheet metal flanges at their meeting edges, the outer face of 65 these flanges being shaped to form channels extending along the flanges, and a series of clamping devices connecting said channel flanges at intervals, each of these devices consisting of a pair of elongated clamping 70 bars slidably engaging the channels, each pair of said bars carrying means for removably clamping them upon said flanges at any desired point, said means including a plurality of separately adjustable connections between the members of each pair of bars. 75

3. A molding apparatus of the class set forth, embodying mold sections having outwardly extending flexible sheet metal flanges 80 at their meeting edges, the outer face of these flanges being shaped to form channels extending along the flanges, and a series of clamping devices connecting said channel flanges at intervals, each of these 85 devices consisting of a pair of elongated clamping bars slidably engaging the channels, each pair of said bars carrying means for removably clamping them upon said flanges at any desired point, said means including arms rigid with said bars, and a plurality of separately adjustable connections between said arms. 90

Signed by me at Chicago, Cook county, Illinois.

ADOLOR HAMEL.
